UNITED STATES PATENT OFFICE.

GEORGE B. KELLY, OF BOSTON, MASSACHUSETTS.

REED-ORGAN.

SPECIFICATION forming part of Letters Patent No. 321,820, dated July 7, 1885.

Application filed February 5, 1885. (No model.)

To all whom it may concern:

Be it known that I, GEORGE B. KELLY, of Boston, in the county of Suffolk and State of Massachusetts, have invented certain new and useful Improvements in Reed or Other Musical Organs, of which the following is a full, clear, and exact description.

This invention has for its object the qualifying or improving of the tone produced by a musical reed, in a reed musical instrument more particularly, so that such tone will partake of and be like a diapason, flute, or pipe tone of a pipe-organ; and the invention consists, in substance, in combination with a musical reed in connection with the usual and proper construction and arrangement of parts for sounding the same in a musical instrument, of a tube, pipe, or hollow cylinder placed over and in communication with the reed-chamber of such reed, provided internally with one or more transverse diaphragms or partitions, each of which diaphragms or partitions has one or more openings or perforations, all substantially as hereinafter fully described.

In the accompanying sheet of drawings is illustrated the present invention, Figure 1 being a view in vertical cross-section of a portion of a reed musical instrument with its musical reed, and having connected therewith a tube or pipe prepared according to this invention. Fig. 2 is a detail cross-section on line 2 2, Fig. 1; Fig. 3, a plan view of one of the diaphragms; Fig. 4, a vertical cross-section of one of the tubes with its diaphragm; Fig. 5, a view in vertical cross-section, in modification; Fig. 6, a plan view of a diaphragm or partition having two openings.

In the drawings, A represents a wind-chest of a reed musical instrument; B, a valve located therein over a passage, C, in the partition D. E is a chamber above such passage C and communicating therewith, in which chamber are two musical reeds, F G, in a reed-block, H, and over openings J K, to their respective chambers L M, each of which chambers has a passage, N, arranged to be opened and closed by a slide or register, P, having openings Q to correspond with the passages N when moved into proper position therefor, the several parts being constructed and ar-

ranged to operate in connection with a force or pressure bellows, (not shown in the drawings,) proper communication being made between the wind-chest and said bellows, in the usual manner, all of which are constructed and arranged for operation, as usual, in reed musical instruments, and needing no particular description herein.

R S are two tubes or pipes, made of wood or of any suitable material and having open ends a b. Each tube is placed and secured in a socket, T, in the block U, so that its lower end, a, will be over and open to a passage, N, of its respective reed-chamber L or M. In each of these tubes is a transverse diaphragm or partition, V, which diaphragm has a central vertical opening or passage, W, through it. The diaphragms or partitions V are made of wood or of any suitable material, are inserted in the tube at any proper points and distances apart, and preferably so as to closely fit the internal periphery of its tube to hold it in its position after being placed, and yet free enough to be moved up and down therein, as desired, in any suitable manner.

With the wind-chest A connected with any suitable force or pressure bellows, and the slide or register P moved into position for its openings Q to be coincident with the passages N, and the valve B opened, air from the bellows passes from the wind-chest through opening C, to and through the reeds F G, into reed-chambers L M, through the opening J K, and out through the passages N, openings Q, in slides, into and through the tubes R S, and the passages W in their respective diaphragms, and sounding the reeds.

The usual and ordinary tones produced by musical reeds, more especially when a force or pressure bellows is used without the tubes R or S and their diaphragms, are more or less harsh, disagreeable, and "reedy," but by the use of a tube, R or S, with its perforated diaphragms applied as described, the tone produced by the same reed will be entirely relieved of such harshness and reedy quality, and will be so qualified and improved that it will be like or resemble the tone of a diapason or flute or pipe tone of a pipe-organ, the tone being smooth, round, and full. The tone produced by such a construction and arrangement

of transverse perforated diaphragms in a tube, as described, can be varied somewhat by arranging the diaphragms in different positions within the tube relatively to the length of the 5 tube and to each other—as, for example, the tone produced by a reed with the arrangement of the diaphragms in the tube R would be softer and not so loud or brilliant as the tone produced from the same reed through the 10 tube S with its arrangement of diaphragms, although each tone would still preserve the character of a pipe-tone.

In arranging a series of such tubes with their diaphragms to a scale of a number of 15 octaves of reeds in a musical instrument, the tubes connecting with the reeds producing the highest notes should preferably be quite short, and the series should gradually increase in length down to the lowest notes, and when 20 such short tubes are used it is preferable to have only one diaphragm or partition, as shown in Fig. 4 in vertical cross-section, which shows a tube with one perforated diaphragm suitable for the upper or highest notes of the 25 scale.

One diaphragm need only be used in any of the tubes of the series, if desired; but better results are produced in the tubes used for the lower and bass notes by having two dia- 30 phragms, as shown.

The locations of the diaphragms in the tubes can be determined and arranged in any suitable manner—as, for example, by testing and trying the tones and adjusting the diaphragms 35 by moving them up or down within the tube until in the right position to produce the quality of tone desired, and when so adjusted they can, if desired, be secured in any suitable manner to prevent accidental dis- 40 placement. They can be set permanently or arranged to be moved as desired; or they can be arranged to be adjusted in any other or suitable manner—as, for example, as shown in Fig. 5, which shows in vertical cross-section a 45 tube, R, in two parts, X Y, one, X, adapted to closely fit over the other, Y, so it can slide up and down thereon similar to telescope tubes. As shown in this figure, one diaphragm, V, is placed at the top of the portion X, and the 50 other at the top of the portion Y, and by sliding the portion X up or down on the part Y the diaphragms will be adjusted as desired. More than two parts, X or Y, can be used if necessary.

55 The diaphragms can be arranged to be moved in the portions X or Y so as to be adjusted in each portion as desired, and also more can be used if deemed necessary.

The diaphragms can be made of flexible 60 material—such as india-rubber, leather, &c.—and secured in any proper manner.

The chamber E need only have one reed in lieu of two, and in such case only one tube would be used, as is obvious.

65 Although the present invention is shown

in connection with parts of a musical instrument constructed and adapted for operation in connection with a force or pressure bellows, obviously it can be used in connection with a musical instrument operated by an exhaust 70 or suction bellows.

If desired, more than two diaphragms with their respective passages W can be used; also the passages W can be of any desired shape in cross-section—such as elliptical, square, 75 &c.—although it is preferable to have them round or circular. The tube or pipe can also be of other shapes in cross-section—such as elliptical or square, &c.—and the diaphragm can have more than one passage through it, as 80 shown in Fig. 6, which is a cross-section on same line as Fig. 2, but showing two passages, W, in the diaphragm, and three or more passages can be made, if desired.

Although this invention is more particu- 85 larly described and shown in connection with a reed musical instrument having reeds for the sounding devices, obviously the invention can be applied to musical instruments having other sounding devices—such as pipes—and in 90 such case the tube could be part of the pipe itself, and provided with the transverse dia- phragms, as described.

I do not claim, broadly, a tube or pipe in combination with a reed and its chamber of a 95 reed-organ, as such is not new; but,

Having thus described my invention, what I claim is—

1. The combination, with the reed and its chamber, of a tube arranged above the regis- 100 ter or slide, and provided with one or more internal transverse perforated diaphragms or partitions, substantially as and for the purpose specified.

2. The combination, with the reed and its chamber, of a tube provided with one or more internal transverse perforated diaphragms or partitions, arranged to be adjusted therein, substantially as and for the purpose specified. 105

3. The combination, with a reed and its reed- 110 chamber, of a tube provided with one or more internal transverse perforated diaphragms or partitions, and arranged to fit within a socket, T, in the block U, substantially as and for the purpose specified. 115

4. In a reed musical instrument, the combination, with its reed and reed-chamber, of a tube made in two or more parts, one or more of which parts are adapted to slide on the other or others, and each provided with one 120 or more internal transverse perforated dia- phragms or partitions, V, substantially as and for the purpose specified.

In testimony whereof I have hereunto set my hand in the presence of two subscribing 125 witnesses.

GEO. B. KELLY.
